UNITED STATES PATENT OFFICE

FRANK B. PRESCOTT, OF TACOMA, WASHINGTON

MERCURY CONDENSER

Application filed August 5, 1930. Serial No. 473,271.

My invention pertains to apparatuses and processes whereby mercury is extracted and reduced from cinnabar, the ore or rock in which mercury is found in the mining industry. In the process, the cinnabar is first crushed into small particles less than an inch in size. From the crushing plant the ore is put through a roasting furnace in which it is exposed to a uniform high heat till all 10 mercury is parted from the rock in the form of mercurial vapor. The vapors or fumes pass from the furnace into a dust collecting multiclone and from thence it is drawn into the condensing apparatus to which my invention pertains.

My invention comprises certain new and useful improvements in the construction, operation and maintenance of the condensing apparatus of the mercury reduction plant. 20 One object of my invention is to obtain a more practical, substantial and economical construction of mercury condensers. Another object of my invention is to provide means whereby mercurial vapors will be more effectively and completely condensed than by processes now in use; and a still further object is to so construct a mercury condenser that can be maintained by replacing certain wornout parts without having 25 to shut down the entire reduction plant.

I attain these and other objects by means of the apparatus illustrated in the accompanying drawings, in which:—

Figure 1 is a top view of a main unit of the condensing apparatus, a part of the collecting compartments being shown in section; Fig. 2 is a side elevation of Fig. 1, a part of the collecting compartments being shown in section; Fig. 3 is a vertical cross section of Figs. 1 and 2 on the line 3—3; Fig. 4 is an enlarged cross section of one of the compartment cleanout doors and a side trough; Fig. 5 is an enlarged top view of one of the recess castings in which the condensing pipes are set; Fig. 6 is a central vertical section through Fig. 5; Fig. 7 is an enlarged view of a standard of the angle iron trestle to support the foot planks between the condensing pipes; Figs. 8 and 11 are respectively a top view and vertical cross section of the re-

movable cast iron top to the condensing pipes. Fig. 9 is a side elevation of two large wood stave tanks, one tank being shown in vertical section; and Fig. 10 is a top view of Fig. 9, one tank being shown in horizontal 55 section.

Similar characters refer to similar parts in the several views.

The first unit of my improved mercury condenser comprises a series of compartments shown and indicated at 1, 2, 3, 4, 5 and 6, all inclosed within a box-like structure 7 made of a strong mixture of reinforced concrete, each compartment being 60 made vapor tight and separated from each other. Compartment 1 is connected through the top with compartment 2 through wrought iron inverted U pipes 1X2. Compartment 2 is likewise connected with compartment 3 by similar pipes 2X3, and the 65 entire series of compartments are thus connected through to compartment 6 as shown and indicated. These pipes are approximately eight inches in diameter and the pipes of each pair are connected near the top by 70 cross pipes of the same diameter.

The mercurial vapor and other fumes are drawn into the compartment 1 through the inlet pipe 8 and the residue of fumes pass 75 out from compartment 6 through the outlet pipe 9 and into and through two wooden tanks hereinafter described for further and more complete reduction.

Each of the six collecting compartments of the vapor condenser has a floor 10 inclined 80 from its center to each side where a close fitting cast iron door 11 provides an outlet through which the mercury and other substances condensed therewith, is scraped out into a concrete trough 12 running along each side of the condenser. This mixture of substances is composed of dust, vaporized acids and moisture extracted from the heated ores. The free mercury gravitates to the centrally 85 inclined bottom of each trough into a central gutter 13 from which it passes into the pipe outlets 14 through which it is conducted into a suitable receptacle conveniently located 90 where it is put into iron flasks for shipment. The residue mud is hoed along each trough 95 100

into a steam jacketed muller 15 where it is mixed with lime, and any mercury remaining therein is worked out by mechanical agitation. All fumes from the muller are returned by means not shown into the vapor conducting pipes or system, and thence into the smoke stack.

It is to be observed that the fumes and gases are drawn through the condenser by a motor driven exhaust fan 16 and the whole apparatus is thus put under suction at all times. This eliminates all danger of salivation of the operators and allows all cleaning, repairing or changes to be made without interrupting the operation of the plant. The exhaust fan is driven at variable speed as condition may require. The condenser is to be housed in an open building, not shown, in which the air will circulate freely to facilitate the cooling of the vapors. If found necessary, a fan driven current of air can be blown about the cooling pipes by means not shown.

One of the improvements I have made in the condenser is in the recess castings 17 set in the top openings of each concrete compartment. These are made to loosely receive and support the upright inverted U cooling pipes. Suitable calking can be inserted about each pipe inside the casting to make the same gas tight. The open top of each cooling pipe is closed with a cast iron cover 18 that can be removed for swabbing the pipes of substance that may collect on their inner surfaces. The cast iron caps are made with a circular groove to receive the pipes. It will be observed that the cap and the recessed castings are so formed that all collections from condensation within the pipes can fall clearly into the several collection compartments. It will be further observed that when the iron cooling pipes become so damaged by the fumes that removal is necessary, they can be taken out one pair at a time and new pipes put in their stead, while the reduction plant is in full operation. Should it be necessary to renew the castings 17 at any time, they can likewise be taken out and new castings put in.

Another improvement is in supporting the foot plank walks between the pipes on suitable iron trestles 20. Heretofore, these plank walks 19 have been supported on brackets fixed on the cooling pipes, making it very difficult to renew the pipes. The planks supported in this way maintain a fixed walk from which the operator can swab the pipes at all times or remove the pipes for putting in new ones.

The concrete compartments are supported on substantial concrete foundations 21 with the hearth 10 about four feet above the floor. This is a convenient height for the operators to scrape out the compartments and hoe the mud along the concrete side troughs 12,

These troughs are turned inward to a central point at one end of the condenser to empty into the muller 15 which is an improvement over the present way of terminating at the two corners of the condenser.

The condenser shown will reduce the fumes from a furnace of approximately seventy-five tons of cinnabar ore per day. Its capacity can be increased by adding one or more compartments and with the required additional connecting pipes, additional length will be obtained in the pipe cooling circulation. The width of the compartments can also be increased and two or more lines of pipes be added and thus enlarge the condenser to reduce the fumes from any size of furnace desired.

The fumes and gases from the fan 16 are exhausted from the pipe 22 into a cone bottom wood stave tank 23 and from thence into a second tank 24, an exact duplicate of tank 23. The gases enter each tank near the top where a deflector 25 gives them a centrifugal motion till they pass out a central vertical pipe 26 with its open end near the bottom of the tank. On entering this pipe 26, the gases pass through a water spray from the nozzle end 27 of the water pipe 28 located in the center of the pipe 26. This spray knocks down any flowered silver and uncondensed gases that may have remained in the fumes after passing through the main condenser heretofore described. From the tank 24, the remaining fumes pass through pipe 29 into the smoke stack not shown in the drawing.

The water spray here described is the only spray used in the entire condensing apparatus and system. The mercury and mud drawn from the bottom of each tank flows through a conductor 30 to the muller where it is worked as the mud from the first unit of the condenser heretofore described. By means of the two wood tanks and the water sprays therein all residue of value in the fumes is condensed and saved. With the combination of apparatus herein shown and the process or system of operation as described, I attain a more complete and effective mercury condenser than has heretofore been used.

I therefore claim:—

1. In a cinnabar-reduction plant, a mercurial vapor condenser, comprising a series of vapor tight collecting compartments adjoining each other, said compartments consecutively being connected by inverted U-shaped cooling pipes, exhaust fan means for maintaining a suction through said collecting compartments and said cooling pipes, and collecting tanks each provided with a deflector disposed for a centrifugal effect at its inlet and with a spray at its outlet, said fan discharging the residue of the vapor or fumes from said condenser centrifugally through said collecting water spray tanks, as shown

and described and for the purposes set forth.

2. In a cinnabar reduction plant, a mercurial vapor condenser, comprising a series of vapor tight collecting compartments adjoining each other, the tops of said compartments being consecutively connected by inverted U-shaped cooling pipes, and exhaust fan means for maintaining a suction through said collecting compartments and said cooling pipes, said cooling pipes being connected with said collecting compartments by means of calcable, loose fitting collar-like iron castings so formed and disposed that said pipes may be renewed while said reduction plant is in operation.

3. In a cinnabar reduction plant, a mercurial vapor condenser, comprising a series of vapor tight collecting compartments adjoining each other, the tops of said compartments being consecutively connected by inverted U-shaped cooling pipes, means for drawing the mercurial vapors through said compartments and said pipes, each of said compartments having a floor which inclines downwardly from a central summit to clean-out iron doors at the sides thereof, and collecting troughs beneath said doors along each side of said condenser, a central gutter being provided in each of said troughs for collecting and disposing of the free mercury therein, and said troughs being made to meet at a common point at the end of said condenser as shown and described and for the purposes set forth.

35 4. In a cinnabar reduction plant, a mercurial vapor condenser, comprising a series of vapor tight collecting compartments adjoining each other, the tops of said compartments being consecutively connected by inverted U-shaped cooling pipes, and exhaust means for maintaining a suction throughout said mercurial vapor condenser, to minimize risk that workmen operating said reduction plant will be injured by fumes and gases escaping from said condenser.

5. In a cinnabar reduction plant, a mercurial vapor condenser, comprising a series of vapor tight collecting compartments adjoining each other, said compartments being consecutively connected by inverted U-shaped cooling pipes, and exhaust means for drawing the fumes under suction through said condenser and discharging the same through a pair of wood tanks, and each of said tanks having means for conducting the fumes centrifugally therein to a central outlet near the bottom thereof, and said outlet being provided with a water spray whereby all values are knocked down as the fumes pass through said water spray as shown and described.

FRANK B. PRESCOTT.
